(57) **CLAIM**

The ornamental design for a garage door handle unit, as shown and described.

DESCRIPTION

FIG. 1 is a front elevational view of the hand member of the garage door opener unit according to the present design, shown separately for ease of illustration;

FIG. 2 is a top view of the hand member of the garage door handle unit according to the present design;

FIG. 3 is a side elevational view of the hand member of the garage door handle unit according to the present design; the other side elevational view being a mirror image thereof;

FIG. 4 is a rear elevational view of the hand member of the garage door handle unit according to the present design;

FIG. 5 is a top view of the step member of the garage door handle unit according to the present design;

FIG. 6 is a front elevational view of the step member of the garage door opener unit according to the present design, shown separately for ease of illustration;

FIG. 7 is a side elevational view of the step member of the garage door handle unit according to the present design; the other side elevational view being a mirror image thereof;

FIG. 8 is a bottom view of the step member of the garage door handle unit according to the present design; and,

FIG. 9 is a reduced front elevational view of the garage door opener unit of the present design as positioned on a garage door.

The broken lines of FIGS. 2, 3, 5 and 7-9 are illustrative of environmental structure only and form no part of the claimed design.
